DESIGN FOR A CUFF LINK

George F. Brecht, Richmond Hill, N. Y.

Application October 27, 1936, Serial No. 65,528

Term of patent 3½ years

To all whom it may concern:

Be it known that I, George F. Brecht, a citizen of the United States, residing at Richmond Hill, L. I., in the county of Queens and State of New York, have invented a new, original, and ornamental Design for a Cuff Link, of which the following is a specification, reference being had to the accompanying drawing forming part thereof.

I claim:

The ornamental design for a cuff link, substantially as shown.

GEORGE F. BRECHT.
